(57) **CLAIM**

The ornamental design for a “square-shaped suction cup hanger.”

DESCRIPTION

FIG. 1 is a front view of a square-shaped suction cup hanger according to the present application;

FIG. 2 is a rear view of the square-shaped suction cup hanger according to the present application;

FIG. 3 is a left view of the square-shaped suction cup hanger according to the present application;

FIG. 4 is a right view of the square-shaped suction cup hanger according to the present application;

FIG. 5 is a top view of the square-shaped suction cup hanger according to the present application;

FIG. 6 is a bottom view of the square-shaped suction cup hanger according to the present application; and,

FIG. 7 is a perspective view of the square-shaped suction cup hanger according to the present application.

The portions of the square-shaped suction cup hanger shown in broken lines in FIG. 6 form no part of the claimed design.
